DESIGN FOR A GLOBE PENDULUM CLOCK

Ben Braude, Chicago, Ill.

Application May 12, 1936, Serial No. 62,604

Term of patent 3½ years

To all whom it may concern:

Be it known that I, Ben Braude, a citizen of the United States and residing at Chicago, in the county of Cook and State of Illinois, have invented a new, original, and ornamental Design for Globe Pendulum Clocks, of which the following is a specification, reference being had to the accompanying drawing, forming part thereof.

Fig. 1 is a front elevational view of the globe pendulum clock, showing my new design.

Fig. 2 is a side view of the same.

I claim:

The ornamental design for a globe pendulum clock as shown.

In testimony whereof, I have affixed my signature to this specification.

BEN BRAUDE.
